UNITED STATES PATENT OFFICE.

AUGUSTUS CICERO FELTON, JR., OF MACON, GEORGIA.

REFUSE AND GARBAGE INCINERATOR.

Application filed January 20, 1926. Serial No. 82,511.

My present invention relates generally to refuse, trash and garbage burners which may also be used to a considerable extent in the incineration of these mixed materials, and my primary object is the provision of an apparatus especially adapted to the burning of bulky trash and refuse more particularly in those localities where refuse for fuel is rarely, if ever, used, and where as a consequence bulky materials are commonly burned as a means of disposal. A further object is the provision of an apparatus of this type which may be easily and quickly started and which, after starting, will be continuously automatic in its action.

A still further object of my invention is the provision of a trash and garbage burner into which the trash or refuse may be indiscriminately dumped, with or without garbage, and which will effectively and automatically bring about continuous and complete ignition and consumption of such waste material without danger of choking and with little, if any, danger of escape of any unburned portions of the charge.

A still further object of my invention is the provision of a trash and garbage burner capable of safely handling large quantities of material and facilitating the disposition of such material properly within the burner.

Another object is the provision of a trash and garbage burner, the arrangement and construction of which precludes dead spots and provides for continuous complete combustion and for the ready easy cleaning thereof to maintain the furnace as a whole at maximum efficiency.

In the accompanying drawings which illustrate my present invention and form a part of this specification:

Figure 1 is a front elevation of my improved apparatus,

Figure 2 is a vertical cross section taken therethrough on the center line of the furnaces,

Figure 3 is a horizontal section therethrough taken on a line above the grates of the furnaces,

Figure 4 is a horizontal section taken therethrough on a line below the grates of the furnaces, and

Figure 5 is a vertical longitudinal section taken centrally through a portion of the stack flue.

Referring now to these figures, and particularly to Figures 1 to 3 inclusive, my

improved apparatus may consist of any desired number of units, each unit preferably comprising a pair of circular furnaces 10 of similar construction, each having an annular wall rising around a furnace floor 11 and surmounted by a dome-shaped top 12, the latter preferably covered by a layer of asbestos 13 and having an upper central opening 14 into which the lower end of a charging chute 15 opens. This chute is preferably disposed vertically above the furnace with its upper end opening through a charging floor 16 extending continuously above the two furnaces and the space therebetween, the upper ends of the two charging chutes 15 being normally closed by doors or manhole covers 17, removal of which permits of readily dumping the trash and refuse directly into the two furnaces and onto the central portions of their floors 11.

The two furnaces preferably have their walls and dome-shaped tops lined with fire-brick and are preferably reinforced by external encircling bands 18, as shown in Figure 1, these bands being connected at spaced points by vertical reinforcing channel bars 19.

The two furnaces are disposed in spaced relation as best shown in Figures 1 and 4 with outlets opening laterally through their walls in opposing relation and into the adjacent end of a horizontally disposed stack flue 20. Communication is had from these outlets indicated at 21, between the furnaces and the stack flue 20, through checkered walls 22, the presence of which avoids the danger of large unburned portions of the charge finding their way into the stack flue 20, although as will be presently seen, this stack in itself forms a large combustion chamber for the complete consumption of any previously unburned portions of the charge, and is for this reason, preferably provided in its length between its end communicating at opposite sides with the two furnaces and its opposite end connecting to any suitable stack (not shown), with draft controlling means including baffles 24 and

25 spaced throughout the length of the flue and alternately upstanding from its lower portion and depending from its top in the manner most plainly seen in Figure 5.

In addition to these features, the stack flue 20 is preferably provided at its end and along its sides with clean out openings 26 normally covered by doors and affording

ready access to the flue in order to maintain the same in a clean condition and in this way avoid any interference with the draft.

It will be noted from Figs. 2 and 3 in particular that the floor 11 of each of the furnaces has an elevated flat area 11^a adjacent to its outlet opening 21 and that around this flat area for substantially its entire space, the floor is inclined downwardly 10 and outwardly toward and to the furnace wall, and is provided in its inclined portion with a series of openings covered by main radial grates 27 and small grates 27^a alternating with the main grates. Each of the 15 grates 27 and 27^a is arranged over and above an ash pit 28 below the base 11, the several ash pits being divided by walls 29 as shown in Figure 4 through which a series of openings 30 provide for communication between 20 the several ash pits below the main grates 27, and a lower central air distributing chamber 31, the latter located immediately below the central portion of the floor 11. Into each of the air distributing chambers 25 31 a forced air supply flue 32 opens, this flue extending beneath a portion of the floor 11 of the furnace as well as longitudinally along and within a portion of the stack flue 20, the outer end of such flue connecting 30 with a force feed fan and its casing 33 which in action directs a continuous supply of air into the respective chamber 31. The fan 33 it will be noted takes in comparatively cool air. This air is in its passage through 35 the air supply 32, especially along and within the stack flue 20, is heated to a considerable extent, and thus when forced into the chamber 31 for distribution through the openings 30 into the spaces below the grates, 40 is in effective condition to materially assist in the combustion within the furnace.

The several ash pits 28 are provided with clean out openings 34 through the furnace wall, normally covered by doors 35, and each 45 furnace also has through its walls openings 36 opposite to and above the several grates, normally closed by doors 37, for the purpose of charging the furnace in the first instance with fuel when it is started, although 50 it is to be understood that instead of charging the fuel into the furnace above the grates, oil burners may be employed through the openings 36 as generally indicated at 38 in Figs. 1 and 2 to be fed through feed lines 55 39 from overhead tanks 40.

In action, the trash and refuse, with and without garbage, is dumped directly through the charging chutes 15 onto the central portions of the furnace floors where this material pyramids so that a gradual continuous feed is thereafter insured onto the several grates. After agitation of this material in the first instance, the action is continuous

and automatic and no further charging of fuel or burning of oil burners is needed 65 through the openings 36. It is of course necessary to charge the furnace sufficiently to keep them going, with the material to be consumed, and it is necessary to clean out the ash pits through the lower openings 34 70 and to clean out the draft flue from time to time through the openings 26.

An apparatus constructed in accordance with my invention will be especially effective and efficient in those continuously warm 75 climates where refuse fuel is rarely, if ever, used, and where bulky materials, large boxes, packing cases, and the like are ordinarily burned as a means of disposal, this furnace being especially efficient in its continuous 80 and automatic consumption of large bulky refuse and trash.

I claim:—

1. A trash, refuse and garbage burner including a furnace having a wall forming 85 therein a furnace chamber and provided with a side outlet for the products of combustion from said chamber, a floor forming the bottom of the chamber having an elevated portion adjacent to the said side outlet and having a downwardly inclined portion around said elevated portion and between the latter and the furnace wall, a stack flue with which the side outlet communicates, a series of grates in the said inclined portion of the floor, means for supplying air upwardly through said grates, including an air distribution chamber below the floor, and an air supply flue communicating with said distributing chamber and 90 extending along, and subject to the heating influence of the stack flue, said furnace having an upper central opening and charging means in communication with said opening. 95

2. A trash, refuse and garbage burner consisting of a furnace having a surrounding wall provided with a side outlet, a floor having an elevated flat portion adjacent to the said side outlet and having its remaining portions inclined downwardly and outwardly from said flat portion to the furnace wall, a series of grates disposed radially in the inclined portion of the floor, each having an ash pit below the level of the floor, said furnace having an air distributing chamber 100 disposed below the central portion of the floor and in communication with the ash pits of certain of the grates, a stack flue into which the side outlet of the furnace wall opens, and means to supply air to the said air distributing chamber including an air supply flue having a portion thereof extending along and within the stack flue, the said air supply flue entering the furnace below 105 the elevated flat portion of the floor.

AUGUSTUS CICERO FELTON, JR.
